UNITED STATES PATENT OFFICE.

JOHN LEE, OF SPRINGFIELD, ILLINOIS.

SWITCH.

1,243,613.

Specification of Letters Patent. Patented Oct. 16, 1917.

Application filed August 11, 1916. Serial No. 114,456.

To all whom it may concern:

Be it known that I, JOHN LEE, a citizen of the United States, residing at Springfield, in the county of Sangamon and State of Illinois, have invented new and useful Improvements in Switches, of which the following is a specification.

My invention relates to mine track switches of the type usually designated as automatic switches, and adapted to be thrown by the locomotive or motor without manual operation by an attendant.

An object of my invention is to provide a device of the above character which will perform its service in an efficient manner, and which will be simple in construction and economical in its operation.

With the above and other objects in view, my invention consists of certain new and useful peculiarities in construction and arrangement of parts, which will be fully described and pointed out in the appended claim.

In the drawings:—

25 Figure 1 is a plan view of the device of my invention.

Fig. 2 is an elevation of my invention.

Referring now to the drawing wherein is illustrated the preferred embodiment of my invention, numeral 1 designates a track of the ordinary type used in mines and 2 a switch track connecting therewith. Numerals 3 and 4 indicate switch tongues which may be pivoted at points 6 and 7 respectively, and which are adapted to open or close the connection to the switch track 2. Switch tongues 3 and 4 are attached in any suitable manner to a connecting bar 5 which is adapted to slide longitudinally beneath the rails of the track, connecting bar 5 extending outward on one side of the track and having pivoted thereto at point 9 an L-shaped bell crank member 8. Bell crank member 8 is pivoted at the angle, designated 45 as point 12, in any suitable manner to one of the cross ties supporting the mine track. The inner leg of said bell crank is pivoted to an actuating arm such as 10 at point 11. Actuating arm 10 extends adjacent and parallel to the outer rail of switch track 2, the opposite end thereof from bell crank 8 being provided with slot 13. A trigger such as 14 is pivoted to the outer rail of track 2, a slot or cut-away portion 16 being provided 55 on the rail therefor. Trigger 14 is pivoted

at point 15 and is provided with a leg 19 which extends downward and passes through slot 13 provided in actuating bar 10. 18 designates springs, one attached on either side of trigger 14 and extending downward 60 and away from trigger 14 and being attached in any suitable manner to the side of the rail.

It is a matter of common practice in mines to make what is designated as "flying switches", in which operation the motor drawing a trip of mine cars passes on to the switch, cutting the trip behind loose at the point of intersection between the switch and the main track and allowing the trip of cars to go on the main track while the motor goes on the switch. In accomplishing this heretofore, it has been necessary to manually throw the switch at the proper time. In the operation of my device it will be seen that 70 the motor may enter the switch as indicated in Fig. 1 and that the trigger 14 may be placed so that the switch may be thrown by the wheels of the motor before the trip of cars following the motor will have sufficient 75 time to enter the switch, the motor being uncoupled from the cars at a point just before the switch has been reached. The switch tongues will then be thrown into position to close the switch by the action of the 80 wheels against the trigger 14.

When the motor moves along the switch track toward the switch, it will also be readily seen that the wheels of the motor will operate the trigger to open the switch, allowing the motor to pass, leaving the switch 85 open behind it.

I also desire to provide my device with a lever, such as 20, for the manual throwing of the switch when so desired, but it is not 90 to be understood that it is desired to cover such a lever by Letters Patent.

From the foregoing description it will be readily seen that the device of my invention will provide an effective means for the automatic operation of the mine switch, which device is inexpensive and simple in construction.

While I have described the preferred embodiment of my invention, I do not wish to 105 be limited thereto, except for such limitations as the claim may import, as it is obvious that the details of construction and arrangement of parts may be varied in many ways.

Having thus described my invention, what I claim is:—

In a device of the character described, the combination with a track and switch therefrom, of a trigger attached to a track rail and normally held in upright position by spring members, spring members, an actuat-

ing bar, a bell crank, and a connecting bar for said switch tongues, substantially as described.

JOHN LEE.
